CLAIM

The ornamental design for a drawer-supporting adjustable rail for attachment to bed side rails, as shown and described.

DESCRIPTION

FIG. 1 is a perspective view of a left hand embodiment of a drawer-supporting adjustable rail for attachment to bed side rails showing my new design;

FIG. 2 is a perspective view of a right hand embodiment of the same;

FIG. 3 is an enlarged left end elevational view of the embodiment illustrated in FIG. 1;

FIG. 4 is an enlarged front elevational view of the same;

FIG. 5 is an enlarged right end elevational view of the embodiment illustrated in FIG. 1;

FIG. 6 is a rear elevational view of FIG. 4;

FIG. 7 is a top plan view of FIG. 4;

FIG. 8 is a bottom plan view of FIG. 4;

FIG. 9 is a perspective composite view combining the right and left embodiments of FIGS. 1 to 2 to form an intermediate supporting rail for two drawers;

FIG. 10 is an enlarged left end elevational view of the embodiment illustrated in FIG. 9; and

FIG. 11 is an enlarged right end elevational view of the embodiment illustrated in FIG. 9.

FIG. 7

FIG. 8.

FIG. 9.

FIG. 10

FIG. 11
